DISHWASHING MACHINE

George M. Gibson, Bellevue, Iowa

Application March 20, 1956, Serial No. 572,730

13 Claims. (Cl. 239—220)

This invention relates to improvements in a dishwashing machine of the character primarily adapted for domestic use. The principles evolved shall, however, be applicable to any kind of dishwashing equipment or to analogous devices.

Some of the most important considerations in a mechanical device adapted for washing dishes relate to the distribution and handling of the washing fluid, the rack construction for the placing of the dishes and the grouping, placement and individual characteristics of the cabinet to accommodate the dish racks and the various functions of the machine, the fluid actuating means, the fluid level and drain control means and the arrangement and disposition of the power and power transmission mechanisms.

One of the objects of this invention is to provide a new and novel fluid actuation and distribution mechanism or means to wash dishes with a high degree of efficiency under comparably short time cycles of operation.

Another object is to provide a cabinet and dish rack combination to provide a compact high capacity washing service in a relatively small total cubical volume machine.

Another object is to provide a cabinet door structure using a unique sealing and venting arrangement.

Another object is to provide a dishwashing machine using a novel fluid level control and drain mechanism.

A still further object is to provide a dual discharge and fluid distribution impeller coating with a reservoir having a predetermined configuration and baffle construction to thereby simultaneously serve two separated article washing zones.

Still another object of the invention is to incorporate fluid driven means that will automatically cause mechanically operated means to vary fluid distribution and impact direction under predetermined fluid washing patterns directed toward and against the articles in the dishwashing machine.

And a still further object is to provide a method of operation for washing dishes wherein an initial relatively cold fluid is introduced and finely actuated toward the article racks to initially form a fluid mist directed for deposition upon the articles in the washing cabinet, this action being followed by larger but variable volume fluid impact under rapidly increasing fluid temperature conditions. With this action of cool prewetting of dishes and cutlery, coagulation and setting of foods such as eggs, cooked cereals, etc., are considerably counteracted and reduced. This paves the way for completely efficient food removal through washing of the articles in the cabinet that are impact cleaned by variable volume fluid actuation following the misting cycle in a continuous process.

Other objects and advantages relating to the dishwashing machine of the present invention shall hereinafter appear in the following detailed description having reference to the accompanying drawings forming a part of this specification.

In the drawings:

Fig. 1 is a front elevational view of the dishwashing

machine embodying the new and novel features of the present invention;

Fig. 2 is a circuit diagram of the washing cycle control mechanism embodied in the dishwashing machine in 5 Fig. 1 to carry out the functions thereof according to predetermined operational sequences at selected time intervals;

Fig. 3 is a plan view on an enlarged scale of the lower operating mechanism compartment of the dishwashing 10 machine as it appears when separated from the cabinet compartment and substantially as viewed along the line 3—3 in Fig. 1;

Fig. 4 is an enlarged vertical transverse cross sectional view of the lower fragmentary portion of the dishwashing 15 machine and as it appears when viewed substantially along the plane of the line 4—4 in Fig. 3;

Fig. 5 is another front elevational view of the machine 20 partially shown in section and without the cabinet door, all as substantially viewed along the line 5—5 in Fig. 3;

Fig. 6 is a vertical cross sectional view on an enlarged scale of the device of this invention as it appears along the plane of the line 6—6 illustrated in Fig. 1;

Fig. 7 is a plan sectional view of the forward part of 25 the cabinet taken along the plane of the line 7—7 in Fig. 6, omitting the lower dish carrying rack to better illustrate the cabinet construction;

Fig. 8 is an enlarged vertical cross sectional view of 30 the front end and door portion of the dishwashing cabinet taken substantially along the plane of the line 8—8 in Fig. 1 to better illustrate detailed improvements in the construction;

Fig. 9 is an enlarged fragmentary vertical cross sectional view taken through one side wall of the cabinet and substantially as viewed along the plane of the line 35 9—9 in Fig. 7;

Fig. 10 is a plan view of the cutlery or silverware basket used in the present machine construction;

Fig. 11 is an end elevational view of the cutlery basket 40 in Fig. 10;

Fig. 12 is an enlarged fragmentary plan view of the front end of the upper dish rack of the present machine;

Fig. 13 is a front elevational view of the upper dish 45 rack;

Fig. 14 is an enlarged front elevational view of the lower dish rack that provides a complementary construction for the upper dish rack;

Fig. 15 is an enlarged fragmentary plan view of one end 50 of the open center washing water impeller that provides the water actuation means to carry out the dual functions of both washing and drying the dishes in the machine;

Fig. 16 comprises a diagrammatic layout of the pre-determined timed washing cycle of operation of the present device, which under parallel consideration with Fig. 2 55 provides a complete illustrative showing of the manner and sequence of operation in carrying out the method of washing dishes according to the principles herein set forth;

Fig. 17 is another plan view of the lower chamber 60 portion of a modified arrangement of the dishwashing machine directed to a variation in the washing water distribution system;

Fig. 18 is a vertical sectional view on an enlarged scale of the machine shown in Fig. 17 and as the same 65 generally appears when viewed along the lines 18—18 in Fig. 17;

Fig. 19 is an enlarged fragmentary plan view of a modified arrangement of an impeller having water driven washing water deflecting wall means associated therewith;

Fig. 20 is an end view of the arrangement shown in

Fig. 19 with certain parts shown in section and as seen along the plane of the line 20—20 in Fig. 19;

Fig. 21 is an end elevational view with parts in section illustrating another modified construction of impeller with a swingably and movable water deflecting wall combination functioning to cause sweep discharge of impeller actuated washing water;

Fig. 22 illustrates a further modified impeller and movable wall deflecting mechanism as viewed from one end thereof with certain parts shown in section;

Fig. 23 is a fragmentary plan view of the mechanism shown in Fig. 22;

Fig. 24 is a detailed transverse vertical cross sectional view of the lower end part of the Fig. 23 construction to further illustrate the arrangement and operation thereof, this view being taken through the cabinet pan immediately in front of and to the right of the mechanism shown in Fig. 23;

Fig. 25 is a fragmentary plan sectional view taken generally axially on one end of a fluid impeller and associated water driven mechanism comprising a further modified means to actuate a rockable deflector through an eccentric driving mechanism; and

Fig. 26 is a vertical cross sectional view taken substantially along the line 26—26 in Fig. 25 to further illustrate details of construction of this latter modified fluid distribution arrangement.

The present invention is generally best shown in Fig. 1 and this assembly comprises the dishwashing machine 1 divided into an upper dish receiving cabinet 2 supported in contiguous relation over a base 3 providing a lower housing or compartment 4 which encloses the operational mechanisms of the machine 1. The cabinet 2 houses the movable dish racks and is provided with a front charging opening 5 closed by a door 6 hinged at 7, the door including a hand grip plate 8 and a centrally arranged vent opening 9. The base 3 carries a front panel 10 having the timer dial 11 and windows 12 forming openings through the panel 10 covered by suitable transparent colored plastic material fronting a pilot light 12 (Fig. 2) carried in the base 3 and comprising a part of the machine operating circuit.

Referring to Figs. 3 and 4, the base 3 herein illustrated has an angle iron framework 13 as the main supporting structure for all the base units and the dish cabinet 2. A composite drain pan-reservoir unit 14 is carried upon the top of the framework 13 and forms a divider or diaphragm separating the washing zone from the operating mechanisms housed within the base 3, with the exception of the impeller 15 which is also disposed in the washing zone and above the diaphragm structure.

The drain pan-reservoir unit 14 comprises a reservoir 16 with a lateral sump 17, sump drain channel 18, silverware or cutlery basket trough 19, all surrounded by the raised drain ledges 20 terminating in an upstand peripheral flange 21 to accommodate and receive the cabinet 2 per se.

Washing water and rinse water is supplied through a hose 22 to a solenoid valve 23 connected through a hose 24 to a diaphragm supported discharge elbow 25 shaped and constructed to deliver cold inlet water toward a given longitudinal point 26 upon the normally revolving impeller 15. With this arrangement and water filling cycle, a fine mist and spray is initially formed to prewet the dishes in cabinet 2. This counteracts setting of foods on the dishes and cutlery to thus enhance the washing operation, the actuated mist and spray becoming heavier and more complete as more return water enters the reservoir 16 by draining off of the ledges 20. When the machine is started by closing the cabinet door 5, a heating unit 27 is energized and the inlet filling water begins to gradually heat after the initial cold water prewetting and filling cycle has been completed. This heating element 27 brings the water up to washing heat and holds it at that temperature, the same element subsequently

providing means to heat the cabinet air for drying the dishes.

A relatively small quantity of washing fluid is used to operate the machine of the present character and design. The maximum fill level may be controlled to bring the normal static level of the water to one gallon capacity that is about coincident with the level line 28 in Fig. 4, or up to two gallon capacity establishing another level 29 as there also indicated. In either case the levels provide considerable impeller exposure to the cabinet washing area or zone and a variable and changeable water actuating discharge results on the basis of a starved reservoir or sump principle being directly responsive to the drain water return variations both in amounts and locations. The speed of the impeller is also a factor in the efficient operation of the machine. With water lever 28 used, the impeller is normally rotated at approximately 1700 r.p.m., this level actually representing a 1 gallon water supply. A selected level 29 which represents a 2 gallon water supply, an impeller speed of 1350 r.p.m. is desirable. In either event, the starved sump or reservoir principle prevails to enhance the method of water impact against the articles being washed in variable degrees of quantity under variable inertia forces plus the unpredicted but complete distribution of the impelled water striking the dishes and cutlery or any articles being washed by the method herein developed.

The water level is established through the drain structure and associated mechanism. A drain fitting 30 connects with the sump drain channel 18 as best seen in Figs. 3 and 4, and a drain hose 31 connects with the fitting 30. Hose 31 includes two horizontally arranged runs 32 and 33 contiguous with an intermediate loop 34, and the hose is then carried as at 35 under the basket trough 19 for exit through one of several openings 36 that are provided in the base apron structure through which the hose is led to a discharge point.

The level of the hose loop 34 determines the static water level in the reservoir changing the elevation of the loop 34 from a raised position as shown at 37 in dotted lines in Fig. 4 to a lowered position as shown in full lines at 38 the water is then drained out of the drain pan-reservoir 14 for the various rinsing and drying cycles that follow in the sequence of operation of the machine.

A hose loop raising mechanism 39 is employed to control the level of the loop. This comprises an arm 40 pivoted at 41 and having a fork 42 to straddle the hose loop 34. A tension spring 43 is connected at 44 with arm 40 and is hooked through an opening 45 in a bracket 46 that is supported upon a cross angle member of the frame 13. A solenoid 47 is also suitably carried upon bracket 46 and the movable pole piece 48 is pivotally connected at 49 with a tailpiece 50 forming a continuation of arm 40 beyond pivot 41 and oppositely related to the arm.

With this construction, the hose loop 34 is normally held in a given raised elevation in respect to the reservoir 16 and sump 17 by the forked arm 40 and spring 43. This position may be determined by employing suitable stop means for the arm as by means of the end of the tailpiece 50 striking against the bracket base 51, or through the limit of motion established by the maximum outward travel of the solenoid pole piece 48. Subsequent energization of the solenoid will lower the loop 34 into a horizontal drain position against the tensile pull of the spring 43 and for the interval that current is supplied to the solenoid.

The power to drive the impeller is supplied by a motor 52 located beneath the upsweep portion 53 of the reservoir 16 and generally in a fore and aft line with the hose manipulating mechanism 39 and the timer 54 mounted upon the front panel 10 of the machine base 3. Brackets 55 and 56 connect with opposite ends of the motor and each bracket has a pivotal bolt connec-

tion at 57 with a base bracket 53 with a locking bolt 59 acting as a means to hold the motor in a given adjusted relation laterally of the machine for belt tightening purposes. The drive from the motor 52 is transmitted through the pulley 60 on motor shaft 61 to the belt 62 that connects with pulley 63 secured to the impeller shaft 64 as best shown in Fig. 3.

The impeller is a squirrel cage unit constructed as a peripheral vane type having an open center structure and with the vanes sweeping through the depressed reservoir 16 and adjacent the wall thereof. As best illustrated in Figs. 3, 4, and 15, the impeller comprises spaced spiders 65 and 66 carried upon shaft 64, with a plurality of longitudinally placed channel vanes 67 secured to the exteriors of the spiders and running parallel to each other and the impeller shaft for substantially the full length of the reservoir. Whatever space prevails between the ends of the vanes and the end walls of the reservoir will provide clearance for water flow around the end portions of the impeller and into the reservoir and sump. Each vane channel is of identical sheet metal construction to provide a double radial vane 68 and 69 having inturned ends 70 and 71 with the vanes joined by the web 72. Thus the impeller vane construction produces longitudinally positioned web closures such as 72 flanked by the impeller peripheral spaces 73 between vanes.

This produces a compound water propulsion action produced by bodily carryover of reservoir water trapped within the vane channels along the reservoir wall with a greater tangential actuation when the vanes are free of the reservoir confines or walls thereof and at the same time excess water in the open center of the impeller and between the vanes is not only subjected to tangential discharge but also to centrifugal throw in a more radial direction between vanes as the particularly discussed portions of the impeller clear the reservoir and reservoir walls. This action compounded by the irregular return flow of expended water in different quantities and at different points produces a very effective washing operation with a minimum of required washing fluid and with a continuous and steady rotation of the impeller.

Suitable bearings 74 and 75 supported upon the fore and aft walls 76 and 77 of the reservoir 16 carry the impeller structure by means of the impeller shaft 64. Bearings 74 and 75 are provided with gaskets to seal the reservoir walls to counteract water leakage at the bearings.

The reservoir includes an added feature in the use of a prearranged baffle wall 78 partially encircling the impeller area at 79 and terminating in an upstanding water deflecting edge section 80. This edge is provided with deformations in the form of vertically arranged fluted portions 81 that fan out upwardly to establish a channeled distribution means in conjunction with the impeller actuation of the dishwashing fluid. This wall 78 and its sectional portions 79 and 80 are held in fixed relation by suitable supporting means fastening the baffle to the fore and aft walls 76 and 77 of the reservoir 16. It should also be noted that the lower terminal edge 82 of the baffle terminates in spaced relation to the reservoir bottom 83 to create a fluid bypass slot 84 facing the sump 17 and cutlery basket trough 19.

As the impeller is rotated in counterclockwise motion, as viewed in Fig. 4, variable portions and quantities of water are actuated through slot 84 into the sump 17 and against or through the basket and into the well 19. The cutlery or silverware basket 85 shown in Figs. 4, 10 and 11 is releasably nested or seated in the basket trough 19 as in Fig. 4. When charged with articles to be washed, the washing action is induced by the impeller water being directed through the bypass arrangement comprising slot 84.

The basket as best shown in Figs. 10 and 11 comprises a wire mesh body 86 crowned and outlined by a stiff

ridge wire 87 with two lifting handles or bails 88 and 89 each provided with outwardly formed pivotal ends 90 and 91 that are pivotally carried or supported in the opposite sides of the wire mesh body 86. The handles 5 each include the cross bar hand grip 92 and the side legs 93 of the handles or bails are disposed in offset planes to clear the basket side walls and to permit the pivotal ends 90 and 91 to occupy the positions shown. The handgrips 92-92 are so arranged as to rest upon the basket ends, as shown in Fig. 10 and each bail is 10 proportioned to permit the grips 92-92 to abut and to meet centrally above the basket for convenience in handling and carrying the basket. As seen in Fig. 11, the basket is polygonal in configuration to fit the basket 15 trough or well 19. The basket sides 94 and 95 fit between baffle 78 and wall 96 of the well or trough and the sloping bottom 97 rests upon the inclined wall 98 of the trough 19.

With the wire mesh basket 85 carried in the base 20 portion of the machine over and adjacent the sump 17, the wire mesh functions as a strainer during the washing cycle. Portions of food or other foreign particles are strained out by the adjacent basket wall 94 and settle or fall down into the sump area and more specifically 25 into the drain channel 18 to be subsequently carried out through hose 31 during a drain cycle interval of operation of the machine brought about by energizing the solenoid 47.

Referring now to Figs. 5 to 8, the cabinet 2 is a four 30 walled structure having a top 99, sides 100 and 101 with a back 102 contiguous with the walls and top. This cabinet as a unit is set down upon the base 3 fitting into the area outlined by the upstanding edge or flange 21 of the drain pan-reservoir 14 and with the cabinet seated 35 upon the drain ledges 20 that are disposed in horizontal coplanar relation. Thus it is understood how the drain-pan-reservoir 14 provides the division diaphragm between the cabinet 2 and base 3, or considered otherwise, between the washing zone and the storage zone of the 40 operating mechanisms and power means. Through the configuration of the diaphragm, the reservoir, sump and basket well or trough are all carried in the same base area or space as the power unit, timer, hose lifter, etc., all arranged in laterally disposed positions within the base 45 as previously set forth. The impeller is likewise substantially confined within the same base area with only a small peripheral portion of the impeller traversing the cabinet zone. For protection, a suitably positioned bowed center wire screen 103 is used over the exposed portion 50 of the impeller, this screen resting in the open mouth area of the reservoir and upon the ledge portions 20 flanking the ends of the reservoir and impeller.

The cabinet 2 presents the front loading opening 5 accessible through door 6 and the cabinet is open at its 55 bottom to receive the actuated washing water from the impeller 15. The front end of the cabinet 2 and the door 6 provide sealing means and steam venting means of the construction best shown in Figs. 6, 7 and 8. The front end of the cabinet is provided with an inturned flange 104 reenforced with a reentrant lip 105, the flange 60 acting as a cabinet facing on three walls thereof to receive the door 6. Across the bottom and front of the cabinet, a door hinge plate or strip portion 106 is provided as a part of the drain pan-reservoir 14 to carry the door in 65 a manner to be explained.

Spaced inwardly from flange 104, the cabinet is provided with a second flange 107 having a reentrant lip 108 to strengthen the same and flange 107 includes an angle strip 109 for securing to the cabinet walls. Flange 70 107 also carries about the three walls of the cabinet, i.e., 99, 100 and 101.

The door 6 is a composite structure consisting of a main vertical panel 110 carrying a flange 111 that is provided around three sides of the door for cooperation 75 with the cabinet flanges 104 and 107. An inturned edge

112 on door panel 110 receives and grasps the angle rim 113 of flange 111. Flange 111 further provides an inwardly disposed rim wall or rack track ledge 114 having a reinforcing reentrant lip 115 that is positioned in a vertical plane spaced inwardly from the cabinet face 5 flange 104 a greater distance than the second cabinet flange 107. This multiple staggered reinforced flange arrangement between the cabinet and cabinet door produces a labyrinth water seal at the front of the cabinet to prevent any impelled water from finding its way out of the surface area bounded by the abutting inturned edge 112 of the door and the adjacent face of the cabinet flange 104.

The entire door 6 is carried upon the water seal hinge 116 that extends the width of the cabinet as best shown in Fig. 7. The hinge 116 comprises the two interlocking semicylindrical beads 117 and 118 on the door 6 and strip 106, respectively. Bead 117 is formed as a part of the door panel 110 reaching into the cabinet opening and depending from the door edge to encircle bead 118. The latter bead is supported upon the front vertical leg 119 of the hinge plate or strip 106 as a part of the upstanding edge 21 on the diaphragm, with the top edge 120 of the panel 10 flanking leg 119 and stopping short of the top thereof for clearance to permit the bead 117 to describe its full arc of operation in bringing the door down into horizontal full open position as illustrated in broken lines in Fig. 8.

The component parts of the hinge 116 are held in assembled operative relation by the locking straps 121 and 122 supported from the track structures as best shown in Figs. 7 and 8. Each strap bears a configuration terminating in a cylindrically formed tip 123 bearing downwardly and outwardly upon the coating hinge beads 117 and 118. By adjusting the amount of pressure or frictional contact of the straps upon the hinge, it is possible to obtain a predetermined looseness or tightness in the swinging resistance of the door.

Door 6 is normally held closed by means of a resilient spool or roller 124 operating in a slot 125 in flange 111 as shown in Fig. 8. Spaced brackets 126 carry sleeves 127 supporting a spring wire or rod 128 that supports the roller 124. By grasping hand grip plate 8 and pulling on the door, the roller 124 will compress and the rod 128 will bend to permit the roller to revolve about edge 129 on flange 104. Reverse operation or door closing snaps roller under and behind edge 129 on flange 104.

Door 6 is further constructed to establish a steam water vapor vent structure as best illustrated in Figs. 6 and 7. A rectangular central boss 130 is formed in the door panel 110 to provide an outwardly positioned vent wall 131 having a large circular opening 132 therein. Opening 132 is outlined by an annular rim or flange 133 positioned inwardly with respect to the cabinet and terminating with a radially outwardly formed reentrant lip 134. A circular panel or baffle plate 135 is carried in spaced relation to the boss vent wall 131 by securing bolt or rivet means 136 (see Fig. 1). This baffle comprises a central wall 137 surrounded by an annular recess or channel 138 that further carries a peripheral rim projection 139 positioned in coplanar relation to the wall 137 of the baffle.

It should be observed that the rim or flange 133 on the cover carries around within the channel 138 and inwardly of the latter and that the lip 134 is also positioned within the recessed part of the annular channel 138 thereby providing a tortuous venting space 140 between panel wall 131 and baffle 135. This permits adequate venting of the cabinet during the washing cycle but particularly during the drying cycle; while water and spray is prevented from escaping through the tortuous space 140.

In its operation about hinge 116, the door 6 also carries a pair of door stop arms 141 and 142 each including an angularly connected tailpiece 143 and 144. These arms are preferably secured to the flange 111 of the door 75

and at the side wall portions thereof as best shown in Fig. 7. When the door is swung open and out to its full horizontal position as shown in broken lines in Fig. 8, the tailpieces 143 and 144 hook behind the side wall runs of the inner cabinet flange 107 holding the door in braced position while in horizontal cantilever location with respect to the cabinet.

It is also the function of one of the stop arms, 141 in this instance, to engage a plunger 145 of a micro switch 146 with the tailpiece 144 to close the circuit leading to the motor and other operating mechanisms of the machine when the door is closed as illustrated in Figs. 2, 4 and 6. Thus, by closing the door 6, the machine circuit can be energized for subjecting the associated operating devices of the dishwashing machine to their respective cycles of operation and as otherwise controlled by the timer dial 11 for off and on positions. With the circuit controlling door operated switch, it is impossible to start the machine unless the charging door 6 is closed.

Referring now more specifically to Figs. 5, 6, 9 and 12 to 14, the cabinet 2 is provided with an internal arrangement that movably supports an upper dish rack 147 and a lower dish rack 148. The upper rack is constructed from a plurality of vertically arranged parallel wires 149 secured to a pair of surrounding perimeter band wires 150 and wires 149 are centrally stabilized by means of the appropriately bent rod 151 secured to the band wires 150 and carrying the individual wires 149 at an intermediate point 152 as best seen in Figs. 12 and 13.

As seen in Figs. 5 and 13, the wires 149 are deformed to include upwardly directed apices 153 carried up on legs 154 and 155 of the rack portion to the left of the rod 151 and with longer depending legs 156 and 157 carrying the upwardly directed apices 158 at the portion of the rack disposed to the right of the rod 151.

With the arrangement of the wires 149 of rack 147 as explained above, downsloping side areas are provided to support cups 159 or bowls 160 in the manner shown to the left in Fig. 5 and to also support glasses 161 and cups or bowls 162 as shown to the right in Fig. 5. The configurations of the tray or rack wires 149 also created sufficient overhead clearance room to avoid contact with dishes and articles being carried upon the lower rack or tray 148.

Both racks are track supported and movable into and out of the cabinet door opening and may or may not be bodily removed from the cabinet if desired. Rack 147 is provided with bracket sets 163, 164, 165 and 166 that carry, respectively, sets of flanged wheels 167, 168, 169 and 170. Units 163 to 165 with wheels 167 to 169 are 45 downwardly directed with the brackets secured to the band wires 150, while each bracket and wheel unit 166 and 170 is upwardly directed and secured to the band wires 150. Angle iron rails or tracks 171 and 172 are secured to the cabinet walls 100 and 101 similar by fastenings such as 173, see Fig. 9, and these tracks run substantially the full length of the cabinet 2. Reactionary rails and wheel guides 174 and 175 are secured to the top 99 of the cabinet.

With this construction the depending bracket and wheel units of rack 147 ride upon supporting rails 171 and 172 and the upwardly disposed brackets and wheel units coast with the ceiling or top tracks 174 and 175. The rack can be pulled out through the door of the cabinet until the rear-most wheels 170 strike angle stops 176 secured forwardly 60 to the cabinet top. In the outer stop position the rack will be suspended in cantilever fashion outwardly of the cabinet door opening 5 for access by an operator. If the rack is to be bodily removed, the front end can be raised to fulcrum the rack upon aligned wheels 169-169 and to lower the aligned rear wheels 170-170 until they clear the angle stops 176 at which time the rack is free and can be pulled forwardly out of the cabinet. Replacement is equally simple by a mere reversal of the manipulation just defined.

Referring now to the construction of the lower rack

148 best seen in Figs. 5, 6, 9 and 14, this assembly comprises a plurality of coplanar deformed wires 176 arranged in vertical spaced planes with respect to each other and secured at their ends to surrounding perimeter band wires 177. Stabilizing rods 178, 179, 180 and 181 are U-shaped and have the front and rear legs secured to band wires 177 and connect at spaced points with each of the wires 176 intermediate their lengths. Rods 178 and 179 are spaced to edgewise carry such larger plates as 182 and 183 on the left in Fig. 5, while rods 180 and 181 are spaced to carry other smaller plates such as 184, 185 and 186 as seen on the right in Fig. 5.

The side portions of the wires 176 as shown at 187 and 188 that flank rods 178 and 179 form upwardly directed wings to hold the plates 182 and 183 in vertical positions and edgewise to the axis of the impeller as well as edgewise to the reservoir baffle wall 78 and its flutes 81. Other side portions of the wires 176 flanking rods 180 and 181 as indicated at 189 and 190 also hold plates 184, 185 and 186 in vertical relation edgewise to the axis of the impeller, reservoir baffle wall 78 and its flutes 81 so that all plates described are subjected to the unpredictable, erratic and variable but efficient inertia packed water action developed in this machine under the method hereinbefore described. The mixed dishes in the upper rack 147 are likewise all edgewise arranged with their edges facing the water action zone of the cabinet as developed by the impeller of the dishwashing machine 1.

Movability of the lower rack 147 is brought about through depending bracket sets 191, 192, 193 and 194 secured to the rack band wires 177 and carrying wheel sets 195, 196, 197 and 198. Channel rails or tracks 199 and 200 are supported on the base frame 13 adjacent the side walls 100 and 101 of the cabinet 2 by bolt fastening units 201, the forward two of which act to simultaneously secure the hinge lock straps 121 and 122 to the track ends adjacent the cabinet door 6.

When the cover 5 is opened horizontally to the broken line position as in Fig. 8, the side portions of the door flanges 111, one of which is referred to as 202 in Figs. 7 and 8 and the other 203 in Fig. 7, are so arranged to assume positions with the rim walls or ledges 114 on the same level with and in line with the lower tracks 199 and 200. This lets the lower rack wheels carry the rack out of the cabinet and along the cover on ledges 114. It is for this purpose that the lower rack wheel sets 195 and 196 are grouped forwardly of the rack; while the wheel sets 197 and 198 are grouped rearwardly, with each group being readily adapted to span the gaps between the front ends of tracks 199 and 200, and their aligned cover bearing rail flange rim units or ledges 114. This provides a smooth running removal or cabinet return of the lower dish rack 148.

The method of washing dishes and the operation of the machine is best demonstrated in the diagrams shown in Figs. 2 and 16. In Fig. 2, the timer 54 includes a timing motor 204 which is supplied with operating current through a switch 205 when the latter is closed by the rotation of the timer dial 11 to start the cycle of operation from Off to On which relationship is also shown in the diagram in Fig. 16. Motor 204, through suitable speed reduction control gearing drives the timer shaft 206 to rotate the switch closing cams 207, 208 and 209 that coat directly and individually with the switches 210, 211 and 212, respectively, in time sequence as determined by the surface contours of each of the cams. The switch 210 controls the solenoid 47 and the drain cycles, switch 211 controls the solenoid 23 and the fill cycle; while the switch 209 controls the heating unit 27 and the impeller driving motor 52.

Current is supplied from the power line over wires 213 and 214. A circuit control switch 146 opens or closes the machine circuit according to the position of the cabinet door 6. When the door 6 is closed, the circuit is capable of being energized subject to the timer

control as regulated by hand through the timer dial 11 to start the machine. Certain of the electrically connected mechanisms run continually for the entire machine cycle while others are intermittent in operation.

Fig. 16 illustrates these sequences of operation and the time devoted to each. The inner ring 215 indicates the minutes of operation after the switch 205 has been moved from 216 to 217 or from Off to On. This action immediately starts the timer motor 205 to regulate the switches 210, 211 and 212. The pilot light 12 lights immediately as shown by "L" in ring 218 of Fig. 16. The timer is "On" and remains on as shown by "T" in ring 219; while the heater as element 27 heats up as indicated at "H" in ring 220.

The washing and rinsing sequences are shown in ring 221 and the duration of each operation is indicated by "W" and wash and "R" for rinse in Fig. 16. The initial water "fill" and subsequent "fills" of water into the reservoir are indicated in ring 222, the drain occurrences "D" in ring 223 and the drying cycle or fan sequences of the impeller with a dry reservoir is shown by "F" in the ring 224.

It should be observed that the first "fill" in segment 225 comes on practically immediately and with the impeller in motion. This action starts the directed spray or mist distribution in the cabinet with cold water to first prewet the dishes to keep the food from setting as has been previously explained in more detail. The washing cycle "W" continues for a 9 minute interval at which time the machine is drained "D." This operation is followed by a rinse cycle "R" from the 10 minute segment to the 19 minute segment with three distinct rinses included as indicated by the first rinse "fill" at segment 226 after the drain at the end of the washing cycle, a second drain "D" and "fill" at segment 227 and a third drain "D" and "fill" at segment 228.

Then a final drain "D" cycle follows in the timed segments and the impeller now becomes or automatically converts into a fan to circulate the cabinet air through the dishes and over the heating element which now heats the air instead of the washing water as in the first portion of the washing cycle.

Referring now to Figs. 17 and 18, the dishwasher here shown incorporates certain modified constructions. The water distribution means here includes, in combination with the impeller 15, a baffle 229 fixed to the end walls 76 and 77 of the reservoir 16 by means of flanges 230 and 231. A pair of bearing straps 232 and 233 are secured to baffle 229 adjacent the ends thereof and these straps with curled ends 234 and 235 rotatably carry pintles 236 and 237 of a spiral vane 238. The vane is freely rotatable in its pintle mountings and each end of the vane is provided with paddles 239 and 240 that are driven in one direction by impeller discharged water. The paddles have hook ends 241 and 242 respectively to induce proper rotation of the vane 238 and in a given direction.

By using the small paddles 241 and 242 at the ends of the vane 238, the latter is slowly rotated by impeller driven water directed along baffle 229. The impeller water also follows the baffle wall to the discharge edge 243 and is then directed or thrown around and against the vane 238 which by its rotation and spiral formation produces a multiple spiral fanning of the water fore and aft of the cabinet as well as from side to side. The fanning water streams are all simultaneously directed through different discharge sweeps and angularities by the rotation of the vane 238 as driven by the paddles at its end. This produces an efficient and effective washing action to thoroughly clean the articles in the cabinet.

Fig. 18 also shows a modified drain hose lifting mechanism 244 comprising a swingable arm 245 carried upon a pivot 246 in a standard 247 secured to one leg 248 of a base angle 249 secured to the base framework 13. A tension spring 250 has one end looped through an open

ing 251 in arm 245 and its other end connected through an opening in ear 252 on the base of the standard 247, the spring functioning to normally hold the hose loop 34 in raised position. A solenoid 253 is secured to the standard 247 and the pole piece 254 is connected by link 255 with an opening 256 in arm 245. When energized, the solenoid lowers the arm to bring the hose into a horizontal drain position, so holding the arm until deenergized to then allow spring 250 to again raise the arm and hose.

In the previous constructions, fixed water deflecting baffle walls were employed for water distribution and directing purposes. Referring now to Figs. 19 and 20, the arrangement here shown incorporates a movable arcuate wall 257 used in conjunction with the impeller 15. Wall 257 is curved to conform with the impeller path of operation and includes a longitudinal reverse fold band 258 to stiffen the wall. Wall 257 is provided with parallel end plates 259 having supporting sleeves 260 that are mounted for rocking upon bearings 261 forming a portion of the impeller shaft bearings 262, the same arrangement being duplicated at both ends of the drain pan-reservoir unit 14.

A water driven mechanism 263 is shown in Figs. 19 and 20 as associated with one plate 259 although the same arrangement may be used at both ends of the movable wall structure. This mechanism 263 comprises three stub shafts 264, 265 and 266 mounted in suitable bearings upon plate 259. Shaft 264 has a water driven propulsion wheel 267 connected thereon to drive a pinion gear 268. Gear 268 meshes with a gear 269 on shaft 265 to further drive an attached pinion gear 270 and the latter meshes with and drives the disc gear 271 on shaft 266. The propulsion wheel 267 is positioned within the open center portion of the impeller 15 as best seen in Fig. 19 and also inwardly of the ends of the impeller vanes 67 to receive water carried around by the impeller between both the curved reservoir bottom and the curved baffle wall 257. This action rotates wheel 267 which action then drives the disc gear 271 at a reduced speed through the gear train on plate 259.

A link 272 is connected with one bent end 273 in opening 274 in disc gear 271 and with another bent end 275 of link 272 mounted to rock in a supporting bearing 276 carried upon a ledge 20 of the drain pan portion of the diaphragm. With this mechanism it is thus possible to rock the baffle wall 257 about the axis of the impeller shaft 64 between the full line showing in Fig. 20 and the two broken line illustrations indicating the limits of motion of the wall. The action is induced by the link 272 operating as a crank unit in conjunction with the disc gear 271 that raises and lowers the entire water wheel and gear train as well as the wall 257 by its connection with the wall plate 259. Thus the described mechanism creates a water directed upward sweep back and forth from side to side through the cabinet and across the full dishwashing zone.

In Fig. 21, a further modification appears in the construction in providing a water distribution action. In general the mechanism 277 in Fig. 21 uses the same baffle wall, water wheel and gear train structure as defined in connection with Figs. 19 and 20 and thus like reference characters will designate these common elements. The variation exists in using brackets such as 278 to mount baffle wall 257 in fixed position and to provide the upper edge of wall 257 with bearings 279 to carry a hinge pin 280 for the swingable support of the deflector 281 also provided with end loops or bearing means to encircle and to fixedly mount the deflector upon the hinge pin 280.

An arm 282 is secured to pin 280 to move as a unit, and a link 283 is pivotally connected at 284 with the outer end of arm 282 and also pivotally connected at 285 with the disc gear 271. When the impeller 15 is in operation, water surges or is directed to drive the water wheel 267 which in turn operates the train of speed reducing

gears, with the disc gear 271 finally operating link 283 to rock the arm 282 whereby the hinge pin 280 causes a back and forth sweep of the water deflector 281. This brings about a water sweep through the cabinet as in the Figs. 19 and 20 construction by a slightly different adaptation of the same general concept.

Another modified water distribution arrangement is shown in Figs. 22, 23 and 24. In this construction an endwise movable baffle wall 286 is used for limited motion in a back and forth direction parallel to the impeller 15. Wall 286 is slidably guided on pins 287 and 288 that are mounted upon the reservoir walls 76 and 77, the wall 286 being provided with apertured clips 289 and 290 to engage over pins 287 and 288 respectively.

The upper portion of wall 286 is flared alternately outwardly from the median plane thereof to provide a plurality of oppositely related water discharge pockets 291 and 292 that are defined by the continuous staggered pocket separating terminal edge 293 of wall 286.

Motion is imparted to wall 286 by a water driven mechanism 294 that employs much the same water wheel and gear train combination used in the modifications in Figs. 19 to 21. As seen in Figs. 23 and 24, an angle plate 295 has an arm 296 with a sleeve 297 rockably supported upon bearing 298 of the shaft journal 299. A water driven paddle wheel 300 is mounted upon a stub shaft 301 on arm 296 to drive a pinion gear 302, the drive then being transmitted to a gear 303, shaft 304 and pinion gear 305 to a disc gear 306 on a shaft 307. Shafts 304 and 307 are also carried upon arm 296.

A link 308 has one end 309 pivoted in an opening in gear 306 and the other end 310 of the link is rockably pivoted in a bearing 311 secured in fixed position to ledge 20 of the drain pan. As the impeller drives the water 35 against the paddle wheel 300, the drive is transmitted through the speed reduction gear train described and by means of link 308 and its connection with disc gear 306 and bearing 311, the angle plate 295 is rocked upon the journal bearing 298.

The motion of the angle plate is then utilized to reciprocate the endwise movable wall 286. This is done by means of the end flange 312 formed as a part of the angle plate 295 by providing a diagonally positioned slot 313 in flange 312 to coact with a fixedly connected pin 314 carried by the movable wall 286. As the angle plate rocks about the bearing 298 and the axis of the impeller shaft, the slot 313 will cam pin 314 in the axial direction of the impeller thereby manipulating the wall 286 in an edgewise fashion and along the peripheral contour of the impeller. With this action, impeller actuated water is guided fore and aft within the machine cabinet by the moving pockets with the same pocket streams being directed laterally and oppositely from the moving wall positions by the alternately staggered pockets described. Here again, an efficient water distribution results as in the other arrangement hereinbefore shown and described.

Another modified construction of a fluid distribution mechanism carried in the reservoir and cooperating with a fluid impeller is portrayed in Figs. 25 and 26. The same kind of impeller and reservoir units are here employed as the fluid propulsion means and they are so identified by the reference characters of the previously given descriptions thereof. The modified mechanism, however, comprises a fluid paddle wheel 315 with vanes 316 positioned inwardly with respect to the impeller 15, the wheel having a hub 317 suitably journaled upon the sleeve end 318 of the impeller shaft bearing 74 and held in place axially by the annular rings 319 and 320. The hub 317 expands into and forms a part of an integral eccentric cam 321 which coacts with the eccentric annulus 322 that has an arm 323 connected therewith as shown in Figs. 25 and 26.

A baffle wall 324 is secured to the front and rear reservoir walls 76 and 77 by bolt and nut means 325

and 326, respectively, that connect with the wall flanges 327 and 328 as shown. Wall 324 has a curved lower portion 329 that follows the impeller curvature and the wall terminates in a straight portion 330 that is normally positioned in an upright manner. Wall 324 supports a pair of spaced bearing straps 331 that have curled bearing sleeves 332 on their upper ends to receive pintles 333 that are connected with a fluid deflector 334. The deflector 334 extends in both directions from the pintle axis to present a larger wall portion 335 above or upwardly from the pintles 333 with a smaller wall portion or tailpiece 336 arranged oppositely to the wall portion 335 and to the other side of the supporting pintles 333 of the deflector 334. A bracket 337 is secured to the deflector 334 in offset relation to the pintle axis and a pin 338 pivotally connects the bracket 337 and arm 323. Retaining means such as pins 339 and 340 keep the pivot pin 338 in its proper relation to the connected parts 323 and 337.

With the dishwashing machine in operation and impeller 15 in motion washing fluid is carried around in counterclockwise direction as viewed in Fig. 26 with some of the fluid being bypassed through slot 341 between wall 324 and the reservoir bottom and with the greater portion of the fluid following wall 329 upwardly and leaving wall portion 330 to engage the deflector 334. In concerted relation, the paddle wheel 315 is rotated by fluid action and this kinetic fluid driving power is transferred to the eccentric means 321-322 to actuate arm 323 for rocking the deflector 334 about its axis for the periodic dispersion of the fluid from side to side across the machine cabinet and in the transverse direction of the machine impeller axis. When the deflector is to the full line side of the wall 324 as shown in Fig. 26, the fluid carries along the bracket face of the deflector. When the deflector moves toward the broken line side of the wall 324 as in Fig. 26, the fluid follows the other face of the deflector with the tailpiece portion 336 aiding this action by its disposition inwardly of wall 324 as considered to the impeller side thereof. Thus the impelled or projected fluid is swept over the dish occupied zone of the interior of the cabinet with the source of the fluid being the unidirectionally revolving impeller that actuates the fluid out of the reservoir.

It might be again emphasized that the fluid or water action will vary in impact and amount due to the variable water return in the machine creating the starved sump and reservoir principle. This action coupled with any of the forms of the water distribution mechanism shown and described contributes to the high efficiency and complete washing action resulting in the machine of the present invention.

Although some preferred constructions of the invention have been disclosed and described, it is possible to employ other similar constructions to further carry out the inventive concepts herein set forth. The invention is, therefore, not to be limited excepting as determined by the breadth and scope of the language defining the invention in the following appended claims.

What I claim is:

1. In a dishwashing machine, a fluid reservoir having a movable fluid deflecting wall, an impeller for said reservoir arranged for coaction with said wall to eject fluid in a given manner out of said reservoir, and fluid driven operating mechanism disposed in the path of fluid ejected by said impeller and connected in driving relationship with said wall and adapted for moving the wall to change the ejected fluid pattern, during the operative dish washing cycle of the machine.

2. In a dishwashing machine as set forth in claim 1, wherein said operating mechanism includes a spiral vane disposed in said path.

3. In a dishwashing machine as set forth in claim 1, wherein said operating mechanism includes eccentric means for changing the positions of said wall.

4. In a dishwashing machine, a fluid reservoir, a fluid deflecting wall, a fluid impeller coacting with said wall, means supporting said wall for movement in a predetermined path with respect to said impeller and between given limits of operation, and fluid driven mechanism in said reservoir connected with said wall and adapted to actuate said wall between its limits of operation, said fluid driven mechanism comprising a gear train including a fluid driven paddle wheel connected to drive said gears, said wheel and gears all being mounted upon a portion of said movable wall, and a crank unit pivotally connected with one of said gears and at a fixed point upon said reservoir to bodily actuate the wall relatively to said reservoir and along the predetermined path of movement of said wall.

5. In a dishwashing machine, a fluid reservoir, a fluid deflecting wall, a fluid impeller coacting with said wall, means supporting said wall for movement in a predetermined path with respect to said impeller and between given limits of operation, and fluid driven mechanism in said reservoir connected with said wall and adapted to actuate said wall between its limits of operation, said fluid driven mechanism comprising a gear train including a fluid driven paddle wheel connected to drive said gears, said wheel and gears all being mounted upon a portion of said movable wall, and a crank unit pivotally connected with one of said gears and at a fixed point upon said reservoir to bodily actuate the wall relatively to said reservoir and along the predetermined path of movement of said wall, said impeller being provided with peripherally positioned vanes operating in a given annular path, and said paddle wheel being positioned within the open center of said impeller and radially inwardly with respect to the path of motion described by said impeller vanes.

6. In a dishwashing machine, a fluid reservoir, a fixed fluid deflecting wall, a movable fluid deflecting wall connected with said fixed wall and forming a contiguous portion thereof, a fluid impeller coacting with said walls to eject washing fluid out of said reservoir in a given manner, and fluid impact operating mechanism connected in driving relationship with said movable wall to actuate the latter relatively to said fixed wall and to thereby change the pattern of discharge of the impeller ejected fluid, said fluid impact operating mechanism being disposed in the path of the impeller ejected fluid to receive its motive power from such fluid.

7. In a dishwashing machine as set forth in claim 6, wherein said operating mechanism includes crank means for actuating said movable wall.

8. In a dishwashing machine, a fluid reservoir, a fixed fluid deflecting wall, a movable fluid deflecting wall connected with said fixed wall and forming a contiguous portion thereof, a fluid impeller coacting with said walls to eject washing fluid out of said reservoir in a given manner, and operating mechanism connected with one of said walls and having operative means connected with the other of said walls to actuate the movable wall relatively to said fixed wall thereby continually changing the pattern of discharge of the impeller ejected fluid, and fluid driven mechanism arranged in the path of the fluid discharged from said impeller and connected with said operating mechanism to motivate the latter.

9. In a dishwashing machine, a fluid reservoir, a fluid deflecting wall traversing said reservoir, an elongated fluid impeller disposed adjacent said wall and coacting therewith to eject fluid out of said reservoir, mounting means for said wall to support the wall for a given displacement with respect to said impeller, and operable means connected in driving relationship with said wall to move the same in relation to the impeller including a driving member to motivate said operable means, said driving member being positioned in the path of fluid ejected by said impeller for actuation by the operation of said fluid impeller, said wall mounting means com-

prising bearing members to support the wall for reciprocable movement lengthwise of the impeller and in a given relation with respect thereto.

10. In a dishwashing machine, a fluid reservoir, a fluid deflecting wall traversing said reservoir, an elongated fluid impeller disposed adjacent said wall and co-acting therewith to eject fluid out of said reservoir, mounting means for said wall to support the wall for a given displacement with respect to said impeller, and operable means connected with said wall to move the same in relation to the impeller including a driving member to motivate said operable means, said driving member being positioned for actuation by the operation of said fluid impeller, said wall mounting means comprising bearing members to support the wall for reciprocable movement lengthwise of the impeller and in a given relation with respect thereto, and said wall being formed with a fluid discharge edge having a predetermined configuration to provide fluid channeling and fluid distribution during the operation of said impeller and under the reciprocation of the wall by said operable means.

11. In a dishwashing machine, a fluid reservoir, a fluid directing wall in said reservoir, a shaft having a fluid impeller supported for coaction with said wall in said reservoir, a movable fluid deflector swingably supported upon said wall and arranged to vary the fluid discharged by said impeller over said directing wall, and operating mechanism connected with said deflector to swing the latter between given limits of operation comprising a drive member supported upon said impeller shaft, an eccentric cam on said drive member, and an operating arm connected with said deflector and having an eccentric annulus coacting with said eccentric cam to actuate the deflector during the operation of said impeller, said drive member comprising a fluid driven wheel loosely carried upon said impeller shaft and arranged to receive impeller actuated fluid whereby to cause swinging of said deflector by said eccentric construction.

12. In a dishwashing machine, a fluid reservoir, a fluid directing wall in said reservoir, a shaft having a fluid impeller supported for coaction with said wall in said reservoir, a movable fluid deflector swingably supported upon said wall and arranged to vary the fluid discharged by said impeller over said directing wall, and operating

mechanism connected with said deflector to swing the latter between given limits of operation comprising a drive member supported upon said impeller shaft, an eccentric cam on said drive member, and an operating arm connected with said deflector and having an eccentric annulus coacting with said eccentric cam to actuate the deflector during the operation of said impeller, said fluid directing wall being arranged to flank said impeller in a generally upright position in said reservoir, and pivotal means to carry said fluid deflector upon the discharge edge of said wall and spaced therefrom.

13. In a dishwashing machine, a fluid reservoir, a fluid directing wall in said reservoir, a shaft having a fluid impeller supported for coaction with said wall in said reservoir, a movable fluid deflector swingably supported upon said wall and arranged to vary the fluid discharged by said impeller over said directing wall, and operating mechanism connected with said deflector to swing the latter between given limits of operation comprising a drive member supported upon said impeller shaft, an eccentric cam on said drive member, and an operating arm connected with said deflector and having an eccentric annulus coacting with said eccentric cam to actuate the deflector during the operation of said impeller, said fluid directing wall being arranged to flank said impeller in a generally upright position in said reservoir, and pivotal means to carry said fluid deflector upon the discharge edge of said wall and spaced therefrom, and said deflector having portions thereof disposed to either side of said pivotal means to thereby change the operative relationships of said deflector portions in respect to said wall.
